Primary Examiner — Prabhakar Deshmukh(74) *Attorney, Agent, or Firm* — Schultz & Associates, P.C.(57) **CLAIM**

The ornamental design for a cabinet handle, as shown and described.

DESCRIPTION

FIG. 1 is a perspective view of a cabinet handle showing our new design;

FIG. 2 is a front elevational view thereof;

FIG. 3 is a left side elevational view thereof;

FIG. 4 is a top plan view thereof; and,

FIG. 5 is a bottom plan view thereof.

The broken lines shown represent unclaimed portions and form no part of the claimed design.
